UNITED STATES PATENT OFFICE

HAROLD HAMMOND, OF WESTPOINT, NEW YORK, ASSIGNOR TO BRENTANO'S, INC., OF NEW YORK, N. Y., A CORPORATION OF NEW YORK.

SCORE-CARD.

No. 806,662.

Specification of Letters Patent.

Patented Dec. 5, 1905.

Application filed April 17, 1905. Serial No. 255,999.

To all whom it may concern:

Be it known that I, HAROLD HAMMOND, captain United States Army, residing at Westpoint, in the county of Orange and State of New York, have invented a new and useful Score-Card, of which the following is a specification.

This invention relates generally to score-cards, and particularly to one adapted for keeping the game of bridge-whist.

The object of the invention is in a ready, simple, and practical manner to facilitate the keeping of the scores of the game and at the same time to exhibit the different values of cards held in one or more hands.

With the above and other objects in view, as will appear as the nature of the invention is better understood, the same consists in the novel form of score-card hereinafter fully described and claimed.

In the accompanying drawing, forming a part of this specification, there is exhibited one form of score-card embodying the present invention, it being understood that changes in the arrangement of the matter exhibited may be made and still be within the scope of the invention, and in this drawing the figure is a view in plan of a score-card forming the subject of this application.

The card is divided into three fields 1, 2, and 3. The field 1 is divided by vertical and horizontal lines into columns 4 and 5, the columns 4 being headed with the plus sign and the columns 5 by the minus sign and the field being headed by the legend "Rubbers."

The field 2, upon which tally of the games is kept, is separated from the field 1 by a perforated line 6 to permit detachment from the latter field when desired and is headed by the legend "Games." This field is provided with vertical rulings, which divide it into columns 8 and 9, headed, respectively, "Points" and "Honors," and above each two of the columns 8 and 9 appear the words "We" and "They."

The field 3 has printed thereon the values of the points and also the values of the cards in one or more hands in securing honors, and by preference the values of the different points and of honors will be indicated by a different

color of ink than that of the remaining printed matter upon the field in order to stand out with distinctness.

In the use of the card a record of the games is kept in the columns 8 and 9, and at the end of the game, or when the play is over, the rubbers are recorded in the columns 4 and 5, and when a sitting is over the plus and minus columns are added and the net total determined at once without further setting down of figures. Should the field 2 become filled before the field 1, it may be detached and another card can be used for the continuation of the games, the original field 1 being employed in recording the new rubbers.

In practice the cards will be bound into pads of ordinary size and in such manner as to facilitate the detaching therefrom of the cards when necessary.

Having thus described the invention, what is claimed is—

1. A score-card divided into three fields, one of which bears printed matter indicative of the value of points and honors, the second field being divided into vertical columns headed respectively plus and minus, and the third field being divided into vertical columns, each two of which are headed respectively "We" and "They," and the individual columns being headed respectively "Points" and "Honors."

2. A score-card divided into three fields, one of which bears printed matter indicative of the value of points and honors, the second field being divided into vertical columns headed respectively plus and minus, and the third field being divided into vertical columns, each two of which being headed respectively "We" and "They," and the individual columns being headed respectively "Points" and "Honors," the latter field being detachable from the second field.

In testimony that I claim the foregoing as my own I have hereto affixed my signature in the presence of two witnesses.

HAROLD HAMMOND.
